RELEASABLE JOINDER LOCK

Marshall I. Williamson, New York, N. Y., assignor to Wedglok Corporation, New York, N. Y., a corporation of New York

Application September 19, 1942, Serial No. 458,927

5 Claims. (Cl. 229—84)

This invention relates to tongue and slit joinders in sheet materials, and particularly to tongue and slit releasable closure locks for wrappers, envelopes, boxes, and like containers formed of sheet paper board or similar material.

The invention is closely related to that disclosed in copending application, Serial Number 458,498, filed September 16, 1942, jointly by myself and W. A. Ringler, and entitled Joinder in sheet materials.

A primary object of the present invention is to provide a joinder of the nature disclosed in the stated copending application Serial Number 458,498, which will be secure and tight and function nicely as a closure lock for containers of the character stated, but which can be very easily unlocked and opened as desired, and re-closed and re-locked thereafter.

A principal feature in the accomplishment of the above object resides in the provision of a movable member for the tongue element including a tab end protruding exteriorly of the joinder, and which is adapted, when such protruding tab end is grasped and pulled, to ride over the interlocking shoulder means of the tongue element, thus depressing such shoulder means and breaking the interlocking engagement thereof with its cooperating edge of the slit element.

Further objects and features of the invention will be apparent from the following detailed description of the preferred embodiments illustrated in the accompanying drawings.

In the drawings:

Fig. 1 represents a perspective view, looking from above, of a wrapper embodying a preferred form of the invention as a releasable joinder lock for the closure panels;

Fig. 2, a fragmentary detail view of the lower closure panel of the wrapper of Fig. 1 subsequent to the release of the joinder lock and the opening of the closure;

Fig. 3, an enlarged fragmentary view illustrating the locked releasable joinder lock of Fig. 1 in inside or bottom plan;

Fig. 3a, a section taken on the line 3a—3a of Fig. 3;

Fig. 3b, a section taken on the line 3b—3b of Fig. 3;

Fig. 4, a view similar to that of Fig. 3, but taken at an intermediate stage of the releasing or unlocking procedure, the view showing how the interlocking shoulder means of the interengaging tongue element is flattened out within the slit element by the release flap;

Fig. 5, an inside plan view considerably re-

duced in size, of the cut and scored blank used in forming the wrapper of Fig. 1;

Fig. 6, an enlarged fragmentary view showing the tongue-forming portion of the blank of Fig. 5;

Fig. 7, a view corresponding to that of Fig. 3, but illustrating a somewhat different form of joinder lock pursuant to the invention;

Fig. 8, a view corresponding to that of Fig. 6, but illustrating the tongue-forming portion of the blank used to form the embodiment of Fig. 7;

Fig. 9, a view corresponding to that of Fig. 7, but illustrating another embodiment of joinder lock pursuant to the invention;

Fig. 10, a fragmentary detail view of the tongue-receiving slit element per se of the joinder lock illustrated in Fig. 9; and

Fig. 11, a view similar to that of Fig. 10, but illustrating the slit-element-forming portion of the cut and scored blank used to form the embodiment of Fig. 9, before it is folded into the position shown in Fig. 10.

The invention is here illustrated as embodied in a mailing wrapper for magazines or the like. In the embodiment of Figs. 1 through 6, the two oppositely extending closure panels 10 and 11, respectively, of the wrapper possess the joinder elements of the invention, and lock together as shown in Figs. 1 and 2.

The wrapper is advantageously folded to final form from a prepared blank, see Fig. 5, cut and scored to provide the bottom wall panel 12, having the closure panels 10 and 11 extending therefrom, as well as the closure supporting flaps 13 and 14, respectively. Each of the closure panels and each of the closure supporting flaps is separated from the bottom panel 12 by one of the four side wall panels 15.

As blanked out at the free end of closure panel 10, the tongue element 16 comprises a base part 17, and mutually similar parts 18 and 18 extending from opposite lateral sides of base part 17 and foldable, on the biased score lines 19 and 19, into superimposed positions upon such base part, so that edges thereof extend along the base line 20, substantially in coincidence therewith, see Fig. 3, and provide shoulder means 21. A part 22 extends from base part 17, between the laterally extending parts 18 and 18, and a plurality of mutually spaced and mutually parallel score lines, here three, provide a zone 23 for the folding of such part 22 over upon the in-folded parts 18 and 18 and the base part 17, and for the allowing of limited movement of such part 22 back and forth lengthwise, relative to the other parts, when folded.

55

The part 22 includes a tab end 22a set between laterally extending ears 22b and 22b, and functions as a release or unlocking member for the joinder lock.

A slit 24 is provided in the closure panel 10 adjacent but spaced apart from the tongue base-line 20 for receiving the tab end 22a and allowing it to protrude outside the wrapper, see Figs. 1 and 2, when the tongue is completely folded and assembled per se.

The joinder lock, as shown in Figs. 1 and 3, is attained by inserting the completely folded and assembled tongue element 16 within the tongue-receiving slit element 25 (formed through and adjacent the free end of closure panel 11) until the shoulder means 21 of such tongue element "clicks" past that defining edge 25a of the slit element 25 which lies farthest from the tip 16a of the tongue element, whereby such tongue element is tightly interlocked with such slit element, the unlocking member 22, with its laterally extending ears 22b, 22b and its tab end 22a, being in the position illustrated in Figs. 1 and 2, effectively holding the folded and superimposed tongue parts 18 and 18 in folded condition against their natural resilient urge from the plane of tongue base part 17, and standing ready for its unlocking function. It should be noted that, in this locked position of the tongue element 16, the edges 10a and 10a of the closure panel 10, which extend from the base of such tongue element in substantially rectilinear alignment with the base-line 20 thereof, abut against the closure panel 11 at either end of the slit element 25, and, thus, add rigidity to the joinder and guard against lateral movement of one of the closure panels relative to the other.

The joinder lock is released or unlocked very easily by the mere grasping of the protruding tab end 22a and by the pulling of the same forward, as indicated by the applied instructions of Fig. 1. Thereby, the laterally extending ears 22b and 22b of the unlocking member 22 are pulled forwardly over the folded and superimposed tongue parts 18 and 18, pressing the shoulder means 21 into the plane of tongue base part 17, and effectively accomplishing release of the abutting engagement of such shoulder means with the defining edge 25a of the slit element, see Fig. 4.

As indicated by Fig. 2, the tongue element 16 may be placed in condition for re-insertion within slit element 25 by merely pushing the tab end 22a into its original position, thereby placing all of the tongue parts into substantially their original positions. Re-insertion will, accordingly, effect re-locking of the closure.

The embodiments of releasable joinder locks illustrated in Figs. 7 through 11 are essentially similar to the above-described embodiment, and, therefore, like parts thereof will be indicated by corresponding reference characters, primed. Since the construction and operation of most parts of the several illustrated embodiments are substantially identical no lengthy explanation is added to what has already been given. It will suffice to point out the differences in construction between the several embodiments, and explain the effect thereof.

The embodiment of Figs. 7 and 8 adds tongue parts 30 and 30, extending from the shoulder-forming edges of tongue parts 18' and 18' being, in effect, merely additional width for such tongue parts 18' and 18' and foldable, on the longitudinal dividing score lines 31 and 31, respectively, into superimposed positions on such tongue

parts 18' and 18' for increasing the effective thickness of the shoulder means 21' by reason of the newly formed longitudinal lines of resiliency which extend along the longitudinal fold lines 31 and 31. Such shoulder means 21' is here coincident with such longitudinal lines of resilience. Such tongue parts 30 and 30 considerably increase the resilient urge of tongue parts 18' and 18' from the plane of tongue base part 17', and, in addition to increasing the effective thickness of the shoulder means 21', strongly urges the laterally extending ears 22b' and 22b' of release or unlocking member 22' away from tongue base part 17', so that, until actuated by the pulling of tab end 22a in the unlocking operation, such ears 22b' and 22b' aid materially in keeping the joinder tightly locked by reason of their abutment against the defining edge 25a' of slit element 25.

The embodiment of Figs. 9, 10 and 11 accomplishes approximately the same results as the immediately prior embodiment, by adding to the tongue-receiving slit element rather than to the tongue element. Here, an extra length 35 is added to the free end of the closure panel 11', and is folded, on the dividing score line 36, into superimposed position on that portion 11a' of the closure panel 11' which lies between it and the tongue-receiving slit element 25', see Fig. 10. It is formed with a short tab 35a extending centrally from its free end, and is held in its fold and superimposed position by insertion of such tab 35a within the tongue-receiving slit element 25'. The resulting bulged end of closure panel 11' bows the defining edge 25a' of tongue-receiving slit element 25' so that it provides a more positive abutment for the shoulder means 21', and, therefore, a more positive interlocking of tongue and slit elements.

In the last two embodiments, that is, in the embodiments of Figs. 7 and 8, and of Figs. 9, 10 and 11, respectively, the tab extension 22a' of release or unlocking member 22' may, advantageously, be made slightly longer than the tab extension 22a of the embodiment of Figs. 1 through 6, as illustrated, for accommodating the extra bulge of tongue element and slit element, respectively.

Whereas this invention is here described with respect to certain preferred specific embodiments thereof, it is to be understood that various changes may be made in such certain specific embodiments, and that various other embodiments may be constructed, by those skilled in the art without departing from the spirit and generic purview of the invention as set forth herein and in the claims that here follow.

I claim:

1. An easily releasable joinder lock in relatively stiff but flexible and resilient sheet material comprising a tongue element and a tongue-receiving slit element, said tongue element having resiliently raised shoulder means which engages that defining edge of said slit element which lies farthest from the tip of said tongue element in interlocking abutting relationship, means standing ready to depress said shoulder means out of its said interlocking abutting relationship, and tab means secured to and extending from said shoulder-depressing means to a location removed from the said joinder lock, said tab means being adapted to effect, when pulled, movement of said shoulder-depressing means for depressing said shoulder means.

2. An easily releasable joinder lock in relatively stiff but flexible and resilient sheet material

comprising, a tongue element formed by folding part of said sheet material upon itself, the said folded part being freely superimposed on the base part of said tongue element and comprising substantially oppositely directed parts which extend from opposite lateral sides of said tongue base part and are infolded upon said base part, and a relatively wide part which extends from between said oppositely directed parts and is folded over upon said oppositely directed parts as infolded upon said tongue base part, edge portions of said oppositely directed and infolded parts forming raised shoulder means due to the resiliency of said sheet material, said shoulder means extending transversely of the length of the said tongue element, said relatively wide part having a relatively narrow tab extension, a tab-receiving slit formed through said sheet material adjacent but spaced apart from and substantially parallel with said raised shoulder means, said tab extension of said relatively wide part being inserted within and passing through said slit to the reverse face of said sheet material; and a tongue-receiving slit element formed in said sheet material, said slit element having a length substantially equal to the width of said tongue element at the location of said shoulder means and being adapted to receive said tongue element in interengaging and interlocking relationship, said tongue element being inserted within said slit element so that the said shoulder means engages in interlocking abutting relationship with that defining edge of said slit element which lies farthest from the tip of said tongue element, said tab extension being available for grasping and pulling in the unlocking of said joinder lock, pulling of said tab extension causing said relatively wide part to pass over said shoulder means and depress the same out of its said interlocking abutting relationship with the said defining edge of said slit element.

3. An easily releasable joinder lock in sheet paperboard material comprising, a tongue element formed by folding part of said sheet material upon itself, the said folded part being freely superimposed on the base part of said tongue-element and comprising substantially oppositely directed parts which extend from opposite lateral sides of said tongue base part and are infolded upon said base part, and a relatively wide part which extends from between said oppositely directed parts and is folded over upon said oppositely directed parts as infolded upon said tongue base part, said relatively wide part being divided from said tongue base part by and being folded on a plurality of closely spaced and mutually parallel score lines, edge portions of said oppositely directed and infolded parts forming raised shoulder means due to the resiliency of said sheet material, said shoulder means extending transversely of the length of the said tongue element, said relatively wide part having a relatively narrow tab extension, a tab-receiving slit formed through said sheet material adjacent but spaced apart from and substantially parallel with said raised shoulder means, said tab extension of said relatively wide part being inserted within and passing through said slit to the reverse face of said sheet material; and a tongue-receiving slit element formed in said sheet material, said slit element having a length substantially equal to the width of said tongue element at the location of said shoulder means and being adapted to receive said tongue element in interengaging and interlocking relationship, said tongue element

being inserted within said slit element so that the said shoulder means engages in interlocking abutting relationship with that defining edge of said slit element which lies farthest from the tip of said tongue element, said tab extension being available for grasping and pulling in the unlocking of said joinder lock, pulling of said tab extension causing said relatively wide part to pass over said shoulder means and depress the same out of its said interlocking abutting relationship with the said defining edge of said slit element.

4. An easily releasable joinder lock in relatively stiff but flexible and resilient sheet material comprising, a tongue element formed by folding part of said sheet material upon itself, the said folded part being freely superimposed on the base part of said tongue element and comprising substantially oppositely directed parts which extend from opposite lateral sides of said tongue base part and are infolded upon said base part, and a relatively wide part which extends from between said oppositely directed parts and is folded over upon said oppositely directed parts as infolded upon said tongue base part, edge portions of said oppositely directed and infolded parts forming raised shoulder means due to the resiliency of said sheet material, each of said oppositely directed parts being folded upon itself longitudinally to provide a longitudinal line of resiliency substantially coincident with said shoulder means and effective in the raising thereof, said shoulder means extending transversely of the length of the said tongue element, said relatively wide part having a relatively narrow tab extension, a tab-receiving slit formed through said sheet material adjacent but spaced apart from and substantially parallel with said raised shoulder means, said tab extension of said relatively wide part being inserted within and passing through said slit to the reverse face of said sheet material; and a tongue-receiving slit element formed in said sheet material, said slit element having a length substantially equal to the width of said tongue element at the location of said shoulder means and being adapted to receive said tongue element in interengaging and interlocking relationship, said tongue element being inserted within said slit element so that the said shoulder means engages in interlocking abutting relationship with that defining edge of said slit element which lies farthest from the tip of said tongue element, said tab extension being available for grasping and pulling in the unlocking of said joinder lock, pulling of said tab extension causing said relatively wide part to pass over said shoulder means and depress the same out of its said interlocking abutting relationship with the said defining edge of said slit element.

60 5. An easily releasable joinder lock in relatively
ly stiff but flexible and resilient sheet material
comprising, a tongue element formed by folding
part of said sheet material upon itself, the said
folded part being freely superimposed on the base
part of said tongue element and comprising sub-
stantially oppositely directed parts which extend
65 from opposite lateral sides of said tongue base
part and are infolded upon said base part, and a
relatively wide part which extends from between
70 said oppositely directed parts and is folded over
upon said oppositely directed parts as infolded
upon said tongue base part, edge portions of said
oppositely directed and infolded parts forming
75 raised shoulder means due to the resiliency of
said sheet material, said shoulder means extend-

ing transversely of the length of the said tongue element, said relatively wide part having a relatively narrow tab extension, a tab-receiving slit formed through said sheet material adjacent but spaced apart from and substantially parallel with said raised shoulder means, said tab extension of said relatively wide part being inserted within and passing through said slit to the reverse face of said sheet material; and a tongue-receiving slit element formed in said sheet material, adjacent an end thereof, said slit element having a length substantially equal to the width of said tongue element at the location of said shoulder means and being adapted to receive said tongue element in interengaging and interlocking relationship, the said end of said sheet

material being folded freely upon itself and secured at said slit element providing a resilient bulge between said slit element and the adjacent end of said sheet material, said tongue element being inserted within said slit element so that the said shoulder means engages in interlocking abutting relationship with that defining edge of said slit element which lies farthest from the tip of said tongue element, said tab extension being available for grasping and pulling in the unlocking of said joinder lock, pulling of said tab extension causing said relatively wide part to pass over said shoulder means and depress the same out of its said interlocking abutting relationship with the said defining edge of said slit element.

MARSHALL I. WILLIAMSON.
